Primary Examiner — Mitchell I. Siegel

(74) *Attorney, Agent, or Firm* — Clement Cheng

(57) **CLAIM**

The ornamental design for a rectangular trampoline and saucer swingset, as shown and described.

DESCRIPTION

FIG. 1 is a top perspective view.

FIG. 2 is a back view.

FIG. 3 is a front view.

FIG. 4 is a right side view.

FIG. 5 is a left side view.

FIG. 6 is a top view.

FIG. 7 is a bottom view; and,

FIG. 8 is a bottom perspective view.

The broken lines shown are included for the purpose of illustrating unclaimed subject matter and forms no part of the claimed design.

1 Claim, 8 Drawing Sheets
